United States Patent Office

Des. 215,977
Patented Nov. 11, 1969

215,977

HORN OR SIMILAR ARTICLE

Charles Berns, Brookfield, Conn., assignor to Edwards Company, Inc., Norwalk, Conn., a corporation of Connecticut

Filed Nov. 14, 1968, Ser. No. 14,460

Term of patent 14 years

Int. Cl. D29—99

U.S. Cl. D72—1

FIG. 1

FIG. 2

FIG. 3

FIG. 4

FIG. 5

FIG. 1 is a front view of a horn or similar article according to my new design.

FIG. 2 is a bottom view of the horn or similar article.

FIG. 3 is a side view of the horn or similar article.

FIG. 4 is a top view of the horn or similar article.

FIG. 5 is a back view of the horn or similar article.

The dominant features of my design reside in the portion shown in full lines.

The medallion is shown in broken line in FIG. 1 for illustrative purposes only.

I claim:

The ornamental design for a horn or similar article, as shown and described.
